UNITED STATES PATENT OFFICE.

GEORGE W. CHECKLEY, OF NEW YORK, N. Y.

BABY-BASKET ATTACHMENT.

1,277,292.

Specification of Letters Patent. Patented Aug. 27, 1918.

Application filed May 23, 1917. Serial No. 170,521.

To all whom it may concern:

Be it known that I, GEORGE W. CHECKLEY, a subject of the King of England, residing at New York, in the county of New York and State of New York, have invented certain new and useful Improvements in Baby-Basket Attachments, of which the following is a specification.

This invention relates to certain new and useful improvements in cradles or baby baskets.

The primary object of the invention is to provide a basket of the type mentioned which can be secured to the side rail of a bed and supported in operative position thereon.

Another object is to provide supporting arms engageable with a bed rail, and a basket detachably associated with said arms.

20 A further object is to provide said arms with means for yieldably supporting said basket.

A still further object is to so incorporate the features of construction above mentioned 25 as to produce a compact and durable device that will be efficient in operation and reasonable as to cost.

The above and other objects and advantages of this invention will be in part described and in part understood from the following description of the present preferred embodiment, the same being illustrated in the accompanying drawings in which—

Figure 1 is a side view of a bed rail illustrating the application of my invention.

Fig. 2 is an end view of my device and

Fig. 3 is a vertical section taken through one of the supporting arms.

In the drawings showing the preferred 40 form of my invention, the numeral 1 indicates an angle iron such as is commonly employed to form one side of a bed frame. Secured to the angle iron and spaced a suitable distance apart are a pair of clamp members 2 and 3, each having the depending end portions 4 and 5. The clamps 2 and 3 are supported on the top portion of the angle iron and the ends 5 engage the depending or side portion of the latter. The ends 4 engage and extend a suitable distance below one lateral margin of the top of the angle iron, and are equipped with thumb screws 6 or other suitable fastening means to retain the clamps in position. A sleeve or socket 7 is associated with each of the ends 5 for a purpose to be hereinafter set forth.

A pair of tubular supporting arms 8 and 9 are provided each having its lower end bent at right angles to provide the lateral extension 10. Angle foot members 11 are provided which have reduced ends 12 adapted to be inserted in the ends of the extension 10 and secured in position by means of rivets or other fastening means. The said angle members 11 have their opposite ends 65 tapered to form the downwardly extending projections 13 which are received in the sockets 7. A set screw 14 is carried by the sockets to retain the supporting arms in position.

A supporting block 15 is positioned in each of the supporting arms 8 and 9 a certain distance above the extensions 10 and is adapted to support a coil spring 16 or other cushioning means. A sliding rod 17 is 75 mounted in the upper end of each arm and is supported by the spring 16 which engages the lower end thereof. The upper end of the rod 17 projects beyond the end of the supporting arm and is bifurcated to provide 80 the branches 18 and 19, with one of which a suitable thumb screw 20 is engaged. A pin 21 is carried by the arm and operates in an elongated slot formed in the rod adjacent its lower end. The slot and pin connection restricts the travel of the sliding rod.

A body portion or basket is indicated at 23 and may be of any suitable material and the shape thereof is equally optional. A plate 24 equipped with a projecting stud 25 is secured to each end of the basket 23, the plates being positioned close to the upper margin of each end, centrally of its lateral margin.

In assembling the device, the clamps are 95 first secured to the side rail of the bed the distance between the clamps being determined by the length of the basket. The supporting arms are then associated with the clamps, and the rods slidably mounted in the upper ends of said arms receive and support the basket 23. As clearly shown in Fig. 1, the studs 25 secured to opposite ends of the basket are received between the branches 18 and 19 of each rod 17, and the thumb screw 20 carried by one of the branches is adapted to be moved into engagement with the stud, and when so engaged will hold the basket against oscillation. When desiring to impart movement of the basket, it is only necessary to move the thumb screw out of engagement with the studs and the basket can 100 105 110

then be rocked or entirely removed from the support.

It is to be understood that the construction shown embodies the preferred form of my invention but I reserve the right to make such changes in the construction and arrangement of the parts as may come within the scope of the appended claim without departing from the spirit of my invention.

10. I claim:

A device of the character described including a pair of clamping members each including a sleeve, a pair of angular members each having one end inserted in a sleeve, 15 a reduced portion on the other end of the angular members, a pair of angular tubular members receiving at one end the reduced extensions to dispose the opposite ends in

vertical positions, a partition block in each vertical portion of each tubular member, 20 slotted and bifurcated rods slidably mounted in the tubular members, pins entering the tubular members to limit movement of the rods, coiled springs interposed between the partition blocks and rods to urge the latter 25 upward, a crib, trunnions at the ends for engagement in the bifurcated portions of the rods, and set screws extending across the bifurcated portions to prevent a displacement of the crib. 30

In testimony whereof I affix my signature in presence of two witnesses.

GEORGE W. CHECKLEY.

Witnesses:

JOHN E. BURCH,

FRANCES HARTMAN.
